UNITED STATES PATENT OFFICE.

JAMES LUCAS TERHUNE, OF HARRISON, NEW JERSEY.

DESIGN FOR A BADGE.

SPECIFICATION forming part of Design No. 21,608, dated June 7, 1892.

Application filed April 14, 1892. Serial No. 429,220. Term of patent 3½ years.

To all whom it may concern:

Be it known that I, JAMES LUCAS TERHUNE, a citizen of the United States, residing at Harrison, in the county of Hudson and State of New Jersey, have invented and produced a new and original Design for Badges; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

The single figure of the drawing is deemed to be sufficient to illustrate the design, and is a plan of the newly-designed badge, showing the decoration embodying the invention.

The leading feature of the design consists in a badge decorated with two circular figures disposed side by side and having figures thereon representing or indicating the eastern and western continents and above said

circular figures the figure of a man, (Columbus.)

In said drawing, *a* indicates the badge; *b b*, two circular figures disposed laterally adjacent one to the other, on the face of one of which is a figure resembling the outlines of North and South America and the other having a figure resembling the outlines of Europe, Asia, Africa, and Australia. Above said circular figures is the figure *c* of a man, (Columbus,) which appears to connect the two figures on which the eastern and western continents are displayed.

What I claim as new is—

The design for a badge, as herein shown and described.

In testimony that I claim the foregoing I have hereunto set my hand this 4th day of April, 1892.

JAMES LUCAS TERHUNE.
